UNITED STATES PATENT OFFICE.

CHARLES J. WATTERS, OF PHILADELPHIA, PENNSYLVANIA, ASSIGNOR TO NORTH AMERICAN LACE COMPANY, OF PHILADELPHIA, PENNSYLVANIA, A CORPORATION OF PENNSYLVANIA.

DESIGN FOR A LACE PANEL.

51,310.

Specification for Design. Patented Sept. 25, 1917.

Application filed April 17, 1917. Serial No. 162,772. Term of patent 3½ years.

To all whom it may concern:

Be it known that I, CHARLES J. WATTERS, a subject of the King of Great Britain and Ireland and the Isle of Man, and a resident of Philadelphia, county of Philadelphia, State of Pennsylvania, have invented a new, original, and ornamental Design for an Article of Textile Manufacture, of which the following is a specification, reference being had to the accompanying drawing, forming part thereof, in which the figure

is a plan view of a lace panel embodying my new design. I also contemplate using such design for other articles of textile manufacture.

I claim:

The ornamental design for an article of textile manufacture, substantially as shown and described.

In witness whereof I affix my signature.

CHARLES J. WATTERS.
